UNITED STATES PATENT OFFICE

SAMUEL SEGAL, OF NEW YORK, N. Y., ASSIGNOR, BY MESNE ASSIGNMENTS, TO SEGAL LOCK & HARDWARE CO., INC., OF NEW YORK, N. Y., A CORPORATION OF NEW YORK

DISPENSING DEVICE

Application filed March 20, 1928. Serial No. 263,117.

This invention relates to a dispensing device and aims to furnish an article of this nature which will have functionally and structurally improved characteristics and which will be of particular value when used as a filling appliance for pocket lighters, it being understood, however, that the device may be employed in numerous different other associations.

10 It is the object of the invention to provide a device of this character, the parts of which will be few in number and individually rugged and simple in construction, these parts being capable of ready assemblage, to 15 furnish a dispensing device capable of operation over long periods of time with freedom from mechanical difficulty and which may be produced at a relatively nominal figure.

A further object of the invention is that 20 of constructing an appliance of this type, the parts of which may be readily detached from each other for cleaning or other purposes and which appliance will have a pleasing and artistic appearance.

25 An additional object is that of furnishing a filling appliance the parts of which will be so proportioned and constructed that a receiving vessel—as, for example, a pocket lighter—will be filled efficiently with an ignitable fluid in an extremely simple and desirable manner and in which the parts may be locked against accidental operation.

With these and further objects in mind, reference is had to the attached sheet of 35 drawings illustrating one practical embodiment of the invention and in which:

Figure 1 is a partly sectional side elevation of a filling device;

Fig. 2 is a perspective view of the exposed 40 portion of the actuating member therefor, and

Fig. 3 is an end view of the nozzle.

In these views the numeral 5 indicates a base of suitable configuration supporting a 45 receptacle body 6, the upper end of which is closed preferably by an integral cap portion 7 formed with a central screw-threaded opening. The receptacle body receives a quantity of volatile fluid as, for example, benzine, and a dispensing structure extends

into the body and is submerged within the fluid.

This structure may include conveniently a tube 8, the lower end of which mounts a screw-threaded plug 9 having a central orifice guarded by a screen 10, and the inner end of this plug providing a valve-seat with which a valve body—as, for example, a ball 11—cooperates in order normally to prevent the fluid from passing through the plug. 55 The tube is formed with an opening immediately above the space occupied by the valve and this opening communicates with a passage 12, which extends upwardly to a point adjacent the upper end of the tube. At this time it will be perceived that the tube preferably forms a part of a cap or plug 13, engaging the screw-threads of the opening formed in the cap portion 7, and that the upper end of the tube is closed by means of 60 a readily removable cap 14. This latter cap is formed with an opening through which extends a slideable rod 15 into the body of the tube 8. The rod mounts at this lower end a piston portion 16 against the under face 70 of which a spring 17 may bear in order to urge normally the piston upwardly to the position indicated in Figure 1. The movement of the parts beyond this point is precluded by forming the rod with a collar portion 18 which engages the under face of the 75 cap to effect this result.

Thus, it will be obvious that upon the rod 15 moving upwardly under the influence of the spring 17 the valve 11 will be unseated, 85 so that fluid will flow through the central portion of the plug. When now the rod is moved downwardly, an escape of the fluid through the opening of the plug 9 will be prevented by the valve and as a consequence, 90 this fluid will be forced into and through the passage 12. It is to be noted, in this connection, that in order to prevent air being trapped within the upper tube end, the latter is formed at a point within the receptacle 95 with an opening 19, so that air may circulate freely. By having this opening communicating with the interior of the receptacle, an escape by evaporation or otherwise of the volatile fluid is prevented.

In the embodiment illustrated, the upper end of the rod mounts a head 20 so that the rod may be freely depressed. Likewise, there is secured to the lower end of this head or knob a U-shaped member 21 having a preferably offset lower end, as indicated at 22. This member is capable of being swung freely from the position indicated in dotted lines to that in full lines, at which latter it will prevent an accidental depression of the plunger, 10 the offset end serving as a bearing surface.

Communicating with the passage 12 is a spout 23 terminating in a nozzle portion 24. This portion, by means of screw threads, (not shown) may be freely detached when necessary. The nozzle is formed with a comparatively fine orifice 25, and thus it will be understood that a penetrating stream will be projected from the end of the nozzle when the rod is depressed. 20

The parts are so proportioned, preferably, that a single depression of the rod will serve effectually to fill a lighter of usual capacity and incident to the fine stream produced, the mass of fibrous material within the latter will be thoroughly charged at all points with the fluid. 25

From the foregoing it will be appreciated that among others, the several objects specifically afore-enumerated are achieved. 30

It will be appreciated, however, that numerous changes in construction and rearrangement of the parts might be resorted to, without departing from the spirit of the invention as defined in the claims. 35

Having described my invention, what I claim as new and desire to secure by Letters Patent is:

1. A dispensing device including a receptacle, a tube extending into said receptacle, a piston, an actuating rod extending into said tube and being secured to said piston, a head secured to said rod and beyond said tube and means extending between said head and tube and exteriorly of said receptacle to prevent relative movement of the parts. 40

2. A dispensing device including a receptacle, a tube extending into said receptacle, a piston, an actuating rod extending into said tube and attached to said piston, a head secured to said rod and beyond said tube and means movably attached to said head and disposable in a position to extend towards the upper tube end to prevent movement of said tube and rod with respect to each other. 50

3. A dispensing device including a receptacle, a tube extending into said receptacle, a piston-actuating rod extending into said tube, a head secured to said rod and beyond said tube and a U-shaped member having its upper ends swingingly secured to said head and extendible to a position towards the upper tube end to prevent relative movement of tube and piston. 60

4. A dispensing device including a recep-

tacle, a tube extending into said receptacle, a piston-actuating rod extending into said tube, a head secured to said rod and beyond said tube and a U-shaped member having its upper ends swingingly secured to said head and extendible to a position towards the upper tube end to prevent relative movement of said tube and piston, said U-shaped member having its base offset to present a bearing portion. 70

In testimony whereof I affix my signature. 75
